Primary Examiner — Clare E Heflin(74) *Attorney, Agent, or Firm* — Polsinelli PC; Adam C. Rehm(57) **CLAIM**

The ornamental design for a light fixture, as shown and described.

DESCRIPTION

FIG. 1 is a front, top, right side perspective view of a light fixture according to the new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front, bottom, right side perspective view thereof.

The broken lines shown on the drawings depict portions of the light fixture that form no part of the claimed design.
